UNITED STATES PATENT OFFICE.

ARTHUR SERVAIS, OF ROUX, NEAR CHARLEROI, BELGIUM.

MACHINE FOR BENDING METAL RODS AND THE LIKE.

Application filed January 7, 1925. Serial No. 1,009.

To all whom it may concern:

Be it known that I, ARTHUR SERVAIS, subject of the King of the Belgians, residing at Roux, near Charleroi, Belgium, have invented certain new and useful Improvements in Machines for Bending Metal Rods and the like, of which the following is a specification.

The present invention relates to a machine for bending iron rods, bars or the like and its object is more particularly to form a U-shaped hook at one end of such bars, under conditions allowing of a large output and ensuring a strict uniformity in the shape and size of the bent articles.

Short metal bars are usually bent into U-shape by means of a reciprocating mandrel co-operating with a die, the bent bars being successively discharged through an opening in the bottom of the die. This process, however, is not suitable for bending long rods or when the shanks of the U are of unequal lengths, on account of the difficulty of removing the bent articles. In such cases the rods are usually bent by hand on a fixed mandrel, whereby two operations are required, one to give the rod an initial bend and the other for sizing the spacing between the shanks. This manner of operating is slow and costly and there is considerable wastage due chiefly to the production of cracks in the bend.

According to this invention I obviate these inconveniences by forcing the metal blank through a die open at both ends, by means of a mandrel or plunger continuously driven in the same direction. The bent rod then is discharged behind the die while the next bending operation takes place, so that the process is very quick and suited to production on a large scale.

In the machine embodying my invention, a plurality of mandrels are mounted one behind the other on an endless carrier and they continuously travel in a longitudinal slot provided in a table onto which the articles to be bent are successively fed. On either side of this slot are arranged stationary guiding members which form together a die open at both ends. Each rod being laid in a given position across the slot is immediately caught by a passing mandrel, pressed against and forced between the guides, whereby it is bent, the bent rod being discharged rearwardly of the guides.

In the accompanying drawing which

illustrates by way of example a machine embodying the present invention:

Fig. 1 is a vertical longitudinal section on line A—B of Fig. 2. 60

Fig. 2 is a plan view of the machine.

Fig. 3 is a cross-section on line C—D of Fig. 2.

The machine herein shown comprises a table consisting of two cast iron plates 1 carried by standards 2 to which they are secured by means, for example, of bolts 3 engaging in brackets 4 on the standards 2 and extending through slots 5 in the plates 1, whereby the width of the free space between 70 the plates 1 can be adjusted.

Under the longitudinal slot 6 thus formed between the plates 1, and parallel thereto extends an endless chain 7 meshing with two carrier pinions 8 one of which is mounted on a driving shaft 8'. On this chain are secured at suitable intervals a number of mandrels here shown to consist each of a rectangular block 9 of a determined thickness. The upper side of the chain 7 is advantageously guided in a U-iron 10 and the mandrels carried thereby project through the slot 6 and continuously travel in the same direction along said slot. 80

On either side of the slot 6 are mounted the guides 11 adapted to co-operate with the mandrels in shaping the rods to be bent. These guides consist of two blocks whose opposite faces are parallel for a part of their length and flare at their front ends as shown at 12. When the rods to be bent are of circular cross-section the operating faces of the guides are preferably curved inwardly as shown in Fig. 3 and provided with a projecting upper edge or flange 13 in order to prevent the rods jumping off the table. The spacing between the guide blocks 11

can be varied by means for instance of screws 14 engaging the blocks 11 and threading into lugs 15 secured to the plates 1. 90

One of the plates 1 further carries two adjustable stops, one 16 next to one of the guide blocks 11 and the other 17 adjacent an edge of the slot 6. The positions of the stops 16, 17 are respectively adjustable transversely and longitudinally of the table, as shown by the directions of the slots 18, 19 in said blocks, through which extend the bolts 20, 21 for securing them in position. A discharge trough 22 may be secured to 110 the table 1 behind the guide blocks 11.

The machine herein shown and described

is arranged and adjusted so as to bend into U-shape one end of iron rods of circular cross-section. The rods coming from an oven where the end to be bent has been suitably heated are successively laid on the table against the stop 16 and the guides 11 in the position 0 shown in dot-and-dash lines in Fig. 2. The endless carrier 7 being set in motion one of the mandrels 9 immediately 10 catches the rod and forces it against the flaring faces 12 of the guide blocks, thus bending the rod (position 0') whereupon the rod is forced between the parallel sides of the blocks 11 whence it emerges (position 15 0'') with the proper bend. While the bending operation takes place the long shank of the rod is forcefully swung inwardly and strikes against the stop 17 which limits its movement, while the flanges 13 prevent the 20 bent portion flying up. As soon as the bent rod has cleared the front part of the guides a new blank is fed to the next mandrel either by hand or by mechanical means, while the first rod is discharged through 25 the trough 22.

The endless carrier can be actuated with great speed, the rods being bent smoothly and without production of cracks, while the co-operation of the mandrels and guides ensures a very accurate sizing of the hooks formed. The relative lengths of the shanks 30 of the hooks can be varied by adjusting the position of the stops 16 and (if required) 17 while the spacing between the shanks can be 35 varied by adjusting the distance between the guide blocks and by replacing the mandrels by others of a different thickness. The machine therefore is adapted to operate on blanks of different sizes, which may require 40 preheating or not, according to their cross sectional dimensions and the nature of the material treated.

It will be understood that constructional changes may be made in the machine 45 claimed, and that the guides for example may comprise a pair of rollers or the like, without departing from the scope of this invention.

I claim:

50 1. In a machine for bending metal rods

and the like, the combination of a die open at both ends, a mandrel, means for driving said mandrel through said die, means for supporting a blank with one end in front of said die, and means adjacent the path 55 of said mandrel for engaging the other end of the blank during the bending operation.

2. In a machine for bending metal rods and the like, the combination of a table having a longitudinal slot, a pair of guides arranged on either side of said slot, a stop near one of the said guides, another stop adjacent the edge of said slot nearest the last mentioned guide, a mandrel projecting 65 through said slot, and means for driving said mandrel between and past said guides.

3. In a machine for bending metal rods and the like, the combination of a table comprising two plates separated by a slot, a 70 pair of guiding blocks on either side of said slot, two slots on one of said plates, one near one of said guides and the other near one edge of said slot, means for adjusting the first mentioned stop transversely of said 75 table, means for adjusting the last mentioned stop longitudinally of said table, means for adjusting the width of said slot, means for adjusting the spacing of said blocks, a mandrel projecting through said slot, and means 80 for driving said mandrel between and past said blocks.

4. In a machine for bending metal rods and the like, the combination of a table comprising two plates separated by a slot, a 85 pair of guiding blocks secured each to one of said plates, the opposite faces of said blocks being parallel to said slot and flaring outwardly, said faces having each a projecting flange along its upper edge, an endless 90 carrier extending under and parallel to said slot, mandrels on said carrier adapted to travel in said slot and between said blocks, a stop for positioning a blank with one end across said slot, and a stop adapted to co-operate with said flanges in directing the movements of said blank.

In testimony whereof I have affixed my signature.

ARTHUR SERVAIS.
